UNITED STATES PATENT OFFICE

172,057

LIGHTING FIXTURE LENS

Ralph Pryne, Pomona, Calif., assignor to Pryne & Company, Incorporated, Pomona, Calif., a corporation of California

Application May 1, 1953, Serial No. 24,799

Term of patent 14 years

(Cl. D48—16)

To all whom it may concern:

Be it known that I, Ralph Pryne, a citizen of the United States of America, residing at Pomona, county of Los Angeles, State of California, have invented a new, original, and ornamental Design for a Lighting Fixture Lens, of which the following is a specification, reference being had to the accompanying drawing, constituting a part thereof:

Fig. 1 is a bottom plan view of a lighting fixture lens, showing my new design;

Fig. 2 is a top plan view thereof;

Fig. 3 is a transverse section on line 3—3 of Fig. 2;

Fig. 4 is an enlarged fragmentary vertical section taken on line 4—4 of Fig. 2; and

Fig. 5 is a fragmentary section showing the part between lines 5—5 in Fig. 3 to a larger scale.

I claim:

The ornamental design for a lighting fixture lens, substantially as shown.
